UNITED STATES PATENT OFFICE.

GUSTAV E. FRITZ, OF CHICAGO, ILLINOIS, ASSIGNOR OF ONE-HALF TO THOMAS G. McMAHON, OF CHICAGO, ILLINOIS.

ARTIFICIAL TOOTH.

1,135,007.

Specification of Letters Patent.

Patented Apr. 13, 1915.

Application filed August 31, 1914. Serial No. 859,277.

To all whom it may concern:

Be it known that I, GUSTAV E. FRITZ, citizen of the United States, residing at Chicago, in the county of Cook and State of Illinois, have invented certain new and useful Improvements in Artificial Teeth, of which the following is a specification.

This invention relates broadly to improvements in artificial teeth, and more specifically to a new and improved anterior detachable or replaceable crown. The invention may also be embodied in bicuspid and molar detachable or replaceable crowns.

In the drawings:—Figure 1 is an enlarged sectional view of my improved anterior crown; Fig. 2 is a view similar to Fig. 1 with my improved detachable pin in place, in the crown; Fig. 3 is a detail view of the pin; Figs. 4 and 5 are cross sections 20 of the pin at points "A—A" and "B—B" respectively, of Fig. 3, and Fig. 6 is a sectional view, enlarged, of a bicuspid crown with detachable pin, showing my improvements.

25 Like characters of reference denote corresponding parts throughout the figures.

1 denotes the anterior crown formed with the labial surface 2, the lingual surface 3, the incisal edge 4, a saucer shaped base 5 and an opening 6 to receive the detachable retaining pin 7.

In Figs. 1 and 2 the dotted line 8 denotes the outline of the lingual surface, as heretofore made, which produced considerable bulkiness in the crown and which had to be ground by the dentist to obtain a perfect articulation or occlusion. This bulkiness was necessary owing to the usual straight pin baked in the crown. It frequently happens that the dentist, when grinding the lingual surface, to obtain perfect articulation or occlusion, will grind such surface to a point at or so near the pin in the crown as to weaken the teeth. I obviate these disadvantages by forming the crown with a peculiarly shaped curved opening 6, making it possible for me to mold and bake a crown without such bulky part of porcelain on the lingual surface, thereby facilitating perfect 40 articulation or occlusion, without grinding crown, and by providing a curved pin 7 to correspond to the opening in the crown, the tooth will resist anterior posterior force during mastication or incising, and prevent

rotation of the crown on the pin. The opening 6, leads into the crown from a central point in the saucer shaped base 5 and is curved, as shown, the labial wall of said opening following approximately the curvature of the labial surface 2 of said crown, 55 the lingual wall of said opening following approximately the curvature of the lingual surface 3 of said crown. This opening is perfectly round to receive a corresponding part 10 of the pin 7, and the base 11 of said opening is convex or rounded, to obviate any sharp edges or corners in the crown, and the end of the pin 12 is similarly shaped, or formed. The lingual wall of the opening 6, in the crown, where it opens out of the 70 saucer shaped base 5 is formed with an enlargement or seat 12 to receive an enlargement, or bulky, or swelled part 13 of the pin 7, which is so made to resist the stress at this particular point in the crown. I have 75 stated that that portion of the pin 10, which enters the crown is round in cross-section. That part of the pin 7 which protrudes from the crown and enters the root canal is oval in cross-section, as at 13, that is, the greatest 80 width of the pin is arranged in such manner as to directly absorb side thrusts and similar forces produced during mastication. The enlargement or seat 12 in the opening 6 in the crown facilitates the easy movement 85 of the crown upon the pin and the shape of said pin when the crown has been cemented in place will insure it against accidental displacement or becoming dislodged under pressure of mastication. There may be several 99 ways of obtaining the correct shaped curved opening in the crown, when molding same. A preferred method is to mold the crown on a pin of correct shape, of a material which will burn away under the intense heat of 95 baking the crown.

In Fig. 6, I have shown my improvements as applied to a bicuspid crown and although not shown, the same may be embodied in a molar crown. The bicuspid is designated 14 having a palatal surface 15, a buccal surface 16, a buccal cusp 17, and a lingual cusp 18. The pin 19 is substantially the same as the pin 7 and the opening 20 corresponds to the opening 6, except that the opening or hold 20 terminates in the buccal cusp. In this way, the pin 19 goes into the bulky buccal cusp instead of toward the sulci, which

would weaken the tooth and entering the buccal cusp lateral force is the better resisted. The protruding end of the pins 7 and 19 may be milled or roughened in any manner, if desired.

What I claim is:

1. In an artificial tooth crown mounting, the combination with a crown having an opening entering the same from a point 10 approximately centrally of its base, said opening being curved in its length, and substantially circular in cross section with its largest dimension at the mouth of the opening, and a pin adapted to fit within said opening and hold said crown in place, said pin having one portion thereof of substantially the same contour as the opening in said crown, and having its largest diameter substantially adjacent the mouth of said

opening when said crown is in position upon 20 said pin.

2. A fastening pin for an artificial crown tooth comprising, a tapering oval shaped lower portion adapted to be secured within a tooth, an upper portion of substantially 25 circular cross section and formed with a reverse curve extending away from and then substantially parallel to the longitudinal axis of said lower portion, the largest diameter of said pin being at a cross section 30 taken through the curve nearest the transverse middle of the pin.

In testimony whereof I affix my signature, in presence of two witnesses.

GUSTAV E. FRITZ.
